UNITED STATES PATENT OFFICE.

FRANCIS LEE STUART, OF WASHINGTON, DISTRICT OF COLUMBIA, ASSIGNOR TO INTERNATIONAL CONVEYOR CORPORATION, OF NEW YORK, N. Y.

RECLAIMING APPARATUS.

1,272,563.

Specification of Letters Patent. Patented July 16, 1918.

Original application filed November 13, 1917. Serial No. 201,798. Divided and this application filed March 4, 1918. Serial No. 220,302.

To all whom it may concern:

Be it known that I, FRANCIS LEE STUART, a citizen of the United States, and a resident of the city of Washington, in the District of Columbia, have invented certain new and useful Improvements in a Reclaiming Apparatus, of which the following is a specification.

This invention relates broadly to an apparatus for reclaiming material in bulk, such as coal, ore and the like, and more particularly to a device of this type which may be bodily moved to a plurality of different operating positions whereby its range of usefulness is increased.

The object of the present invention is to provide a reclaiming apparatus which may deliver at will to either one of a pair of parallelly extending conveyers, and which may be bodily moved to coöperate with different pairs of conveyers.

This application is a division of my pending application Serial No. 201,798, filed Nov. 13, 1917, and the claims herein are confined to the novel features of the conveying apparatus before referred to.

My improvements are illustrated in the accompanying drawings, in which—

Figure 1 is a plan view diagrammatically illustrating a system employing my improved reclaiming apparatus.

Fig. 2 is a side view of a portion of the reclaiming apparatus illustrated in Fig. 1, showing the digger at right angles to the reclaimer.

Fig. 3 is a side view of the traveling digger.

In storing material in bulk, it has been found advantageous in some instances to provide a plurality of storage piles lying adjacent each other and separated by a comparatively narrow space. By reason of this system of storage a single conveyor may be provided between adjacent storage piles thereby decreasing the initial cost of installation, and the cost of up-keep. It is desirable in such a system, to provide a single reclaiming unit which may be bodily moved to coöperate with different pairs of adjacent conveyers, and operated to deliver at will to either of said conveyers. In order to reach all of the material between the conveyers the reclaiming apparatus preferably comprises a digger adjustable longitudinally

thereon so as to deliver thereto at any desired point.

Referring more particularly to the drawings, I have illustrated a system employing a plurality of traveling conveyers 1 extending through the spaces between adjacent storage piles S. These piles are formed from a main source of supply at times when there are no cars C, or the like, available for loading. Piling trimmers 2 constructed in a manner described in my Patent No. 1,241,953, of Sept. 25, 1917 may be employed for this purpose. The carriers 1 are preferably disposed in pits 4 having rails 5 extending parallel to the carriers on opposite sides thereof along which travels the reclaiming apparatus R.

In its preferred embodiment the reclaiming apparatus comprises trucks 6 mounted on wheels 7 and propelled by any suitable source of power 8 so that the same may be moved to the desired position along the trackways 5. Mounted on the trucks and extending transversely of the space intervening between adjacent carriers, is a conveyor frame 9 carrying an endless conveyor 10, of any well known construction adapted to be driven by a motor or the like 11 mounted in the frame. At its opposite ends, the conveyor passes around tripper or discharge rolls 12 disposed to extend through the sides of the hoppers 14 carried by the trucks and having their discharge ends 15 arranged directly above the upper run of the carriers 1. The motor 11 is so constructed that the conveyor 10 may be driven in either direction at will for supplying either one of an adjacent pair of traveling carriers 1.

The frame-work 9 for the reclaiming conveyor 10 is provided on its upper surface on opposite sides of said conveyor with rails 15 having up-turned ends 16 constituting stops. Traveling on the rails 15 is a truck 17 supported on flanged wheels 18 and propelled by a motor 19 through the gearing 20. Mounted on the truck 17 is a turn-table 21 adapted to turn on the anti-friction rollers 22. Extending centrally through the turn-table is a hopper 24 having oppositely extending discharges 25 either of which may be utilized at will according to the direction of travel of the reclaiming conveyor. The hopper 24 is supplied with material by

- the digger 26 mounted in the frame 27. In order to accommodate any unevenness in the ground on which the storage piles are formed and to permit the reclaiming of material from different heights, the turn-table 21 carries adjusting means 28 secured to the digger frame 27 so that the same may be vertically adjusted. This adjustment is clearly indicated in dotted lines in Fig. 3.
10. From the foregoing it is believed that the operation of my improved reclaiming apparatus will be obvious. In the reclaiming operation, the reclamer R is moved along the trackways 5 until the digger 26 comes 15 into engagement with the toe of the pile. The digger is then operated by the motor 29 for elevating material into the hopper 24. Through the system of conveyers described, this material reaches one of the traveling 20 carriers 1 by means of which it may be transferred to loading trimmers 30, similar in nature to the trimmers 2 already described. After one of the piles S is completely exhausted or after all of the cars adjacent a 25 particular carrier are filled, the entire reclamer R is run to the end of the yard and onto the transfer table 31 where it is shifted sidewise into a position where it can be run onto an adjacent pair of tracks. By 30 reason of this particular construction, a single reclaiming apparatus is operative over a comparatively large area, and it can be moved to any point within such area and effectively coöperate with fixed loading devices.
45. Inasmuch as changes may be made in the structural embodiment of the apparatus herein disclosed without departing from the spirit of the invention it is intended that the drawings shall be considered as illustrative of a preferred form, rather than in a limiting sense.
1. I claim as my invention:
1. An apparatus for reclaiming material, comprising two parallel belt conveyers, a truck movable to any desired extent over each of said belts, a hopper supported by each truck and delivering to the belt conveyer beneath it, a horizontally arranged frame supported at its opposite ends by the trucks, a horizontally arranged conveyer
- 50 mounted in said frame and which delivers to said hoppers, a motor carried by the frame for moving said last-mentioned conveyer in opposite directions, a truck mounted to move longitudinally over said frame, a hopper carried by said truck which delivers to the conveyer on said frame, and a digger extending sidewise from the frame and pivotally connected with said last-mentioned truck to move about a vertical axis. 55
2. An apparatus for reclaiming material, comprising two parallel belt conveyers, a truck movable to any desired extent over each of said belts, a hopper supported by said trucks and delivering to the belt conveyer beneath it, a horizontally arranged frame supported at opposite ends by the trucks, a horizontally arranged conveyer mounted in said frame and which delivers to said hoppers, a truck mounted to move longitudinally over said frame; a turn-table on said truck, a hopper carried by said turn-table and which delivers to the conveyer on said frame, and a digger supported by said turn-table 65 projecting sidewise therefrom, turning therewith about a vertical axis and pivoted to move also about a horizontal axis. 70
3. An apparatus for reclaiming material, comprising two parallel belt conveyers, a truck movable to any desired extent over each of said belts, a hopper supported by each truck and delivering to the belt conveyer beneath it, a horizontally arranged frame supported at opposite ends by the trucks, a horizontally arranged conveyer 75 mounted in said frame and which delivers to said hoppers, a truck mounted to move longitudinally over said frame, a turn-table on said truck, a hopper carried by said turn-table and which delivers to said conveyer on said frame, and a digger supported by said turn-table adapted to turn therewith and to be shifted from one side of said frame to the other and also pivotally connected with the turn-table to move about a horizontal axis, and means interposed between the inner and outer ends of the conveyer for moving it vertically. 80
40. In testimony whereof, I have hereunto 85 subscribed my name.
- FRANCIS LEE STUART. 90
